SAFETY MEANS FOR LEAVING DOORS AJAR

Charles P. Kessler, Bronx, N. Y.

Application May 25, 1950, Serial No. 164,215

1 Claim. (Cl. 151—41.76)

1

This invention relates to new and useful improvements in safety means in connection with leaving a door "ajar," and may be equally applicable to windows, etc., and it has for its object to provide a device that will prove sturdy in use, and capable of resisting all attempts to disengage the chain holding said door ajar, or loosening, or unscrewing the mechanism attached to the frame of a door and to which mechanism one end of the chain is secured, while the other end of said chain is made to engage means arranged upon the door proper and adapted to receive said chain in such a manner as to make it impossible to disconnect the chain from said door.

With the above and other objects in view, this invention consists of the novel features of construction, combination and arrangement of parts, hereinafter fully described, claimed and illustrated in the accompanying drawing, forming part of this application, and in which similar characters of reference indicate corresponding parts in all views, and in which—

Figure 1 is a side elevational view of my device connected to a door and its frame.

Figure 2 is a top plan view of my said device.

Figure 3 is a view taken on the line 3—3 in Figure 1; while

Figure 4 is a view taken on the line 4—4 in Figure 1.

Referring more particularly to the drawing, the numeral 10 indicates a chain for securing a door 11 to a frame 12, when said door is left ajar a predetermined distance.

A member 13, fixedly attached to the frame 12, is detachably provided with a shank 19 terminating in an eyebolt 14, to which the chain 10 is permanently secured.

The member 13 comprises, as shown in Figure 4, a bottom plate 15 fixedly secured to the frame 12 in any suitable manner, such, for instance, as by screws. The said plate 15 is at its center formed with an upwardly extending peripheral flange 16 adapted to receive within the latter a nut 17, as said flange 16 surrounds said nut 17 and is bent over the edge of the latter so as to secure said nut solidly in place. The nut 17 has a threaded aperture 18 in the center thereof adapted to receive and engage the correspondingly threaded shank 19, which terminates in the aforementioned eyebolt 14.

A face plate 20 of a shape to embrace said nut 17 and flange 16, is mounted upon the bottom plate 15, before insertion of the shank 19 and secured to said bottom plate and the door frame 12 by screws 22, as shown in Figure 2.

2

The said face plate 20 has upwardly extending lips 42 snugly engaging the sides of the shank 19, whereby to prevent the latter with its eyebolt 14 from turning, and at the same time securing said shank in its threaded position; the said shank 19 and eyebolt 14 are also adapted to receive the ring 26 of the chain 10, when the latter is not in use.

It will thus appear through the aforesaid arrangement, that with the chain fastened to the door and frame, it will be impossible to unscrew the member 13, or the shank 19, because, as to the latter, any attempt to unscrew said shank would be prevented by the lips 42, while at the same time the chain would twist around said shank, and thus tend to close the door.

A plate 23 is attached to the door 11 by screws 24 and, if desired, rivets 41. An elongated corrugated hook 25, shown herein of a substantially rectangular shape, is formed integral with the plate 23; said hook is formed with an extended curvature in the bending thereof, as shown at 36 in Figure 2, in order to avoid an abrupt bending of said hook at the very edge of the plate 23, which would tend to weaken the strength of the hook.

The hook 25 is adapted to receive a ring-member 26 at the end of the chain 10, thus permitting a door to be left securely ajar, as it is understood that the chain is of such limited length, as not to permit anybody to disengage the ring-member from the hook 25, due to the length of the latter; such disengagement of the ring-member from the hook may only be accomplished, when the door is actually, or nearly shut.

In order, when the door is left ajar by means of the chain 10, to secure said door in a fixed position, an elongated bar 27, terminating in a hook 28, is pivotally secured by means of a screwbolt 32 to an outwardly and upwardly extending projection 31 formed on the plate 23. The hook 28 of the said bar 27 is adapted to engage an eyelet 29 formed in an upwardly extending portion 30 integral with the face plate 20.

The proposed use of said bar 27 has been indicated in dotted lines.

When not in use, the bar 27 may be swung into neutral, or resting position, to be thus held by the lug 35 formed integral with the plate 23.

It is obvious that changes may be made in the form, construction and arrangement of the several parts, as shown, within the scope of the appended claim, without departing from the spirit of the invention, and I do not, therefore, wish to

limit myself to the exact construction shown and described herein.

What I claim as new, and desire to secure by Letters Patent of the United States, is:

In a device of the class described, means for attaching a safety chain to a door frame, comprising a bottom plate having an opening therethrough terminating in a non-circular enlarged recess in the bottom of said plate, a nut fitted within said recess and being held in position therein, said nut having a threaded aperture, a face plate embracing the top and sides of said bottom plate, an eyebolt having a shank threaded in said aperture, said face plate being formed with upwardly extending lips engaging the sides of the eye of said eyebolt, whereby to prevent

the latter from turning, and means for securing said bottom plate to said door frame.

CHARLES P. KESSLER.
